(57) **CLAIM**

The ornamental design for a shoe insert with electronic data module, as shown and described.

DESCRIPTION

FIG. 1 is an isometric view of a shoe insert with electronic data module showing our new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken line showing of the remainder of the shoe insert and the bottom and sides of the housing for the electronic module is for illustrative purposes only and forms no part of the claimed design.
